UNITED STATES PATENT OFFICE.

MORRIS E. CONN, OF PHILADELPHIA, PENNSYLVANIA, ASSIGNOR TO THE ACME STAPLE COMPANY, LIMITED, OF SAME PLACE.

DESIGN FOR A FEMALE MEMBER FOR DEVICES FOR LOCKING FORMS OF TYPE, &c., IN CHASES AND FRAMES.

SPECIFICATION forming part of Design No. 31,260, dated July 18, 1899.

Application filed February 28, 1899. Serial No. 707,224. Term of patent 14 years.

To all whom it may concern:

Be it known that I, MORRIS E. CONN, a citizen of the United States, residing in the city of Philadelphia, State of Pennsylvania, have invented and produced a certain new and original Design for the Female Member of Printers' Devices for Locking a Form of Type in a Chase, of which the following is a full, clear, and exact description, reference being had to the accompanying drawings, forming a part of this specification.

My invention relates to a novel design in form or configuration of the female member of a device used by printers for locking a "form" of type in chases and frames and is comprised within the technical term "furniture;" and my new design for such a device is shown in the accompanying drawings, in which—

Figure 1 is a perspective view from one side of the device, and Fig. 2 is a like view from the opposite side.

The design consists of the straight-faced end portion A, having projecting arm C at right angles thereto, the latter being formed with a trough-like cavity or recess E, with 25 serrated lateral edges e, adapted to receive an opposite member described in an application now pending, Serial No. 720,305, filed June 12, 1899, for patent therefor.

Having thus described my invention, what 30 I claim as new is—

The design for the female member of a device for securing a "form" of type, &c., in chases and frames, substantially as described.

In testimony whereof I have hereunto af- 35 fixed my signature this 24th day of February, A. D. 1899.

MORRIS E. CONN.
